United States Patent Office.

SAMUEL G. CABELL, OF QUINCY, ILLINOIS.

Letters Patent No. 65,873, dated June 18, 1867.

IMPROVEMENT IN COPYING-PRESSES.

The Schedule referred to in these Letters Patent and making part of the same.

TO ALL WHOM IT MAY CONCERN:

Be it known that I, SAMUEL G. CABELL, of Quincy, in Adams county, and State of Illinois, have invented a new and useful Improvement in Copying-PresSES; and I do hereby declare that the following is a full, clear, and exact description thereof, reference being had to the accompanying drawings, through letters of reference marked thereon, forming part of this specification, and in which—

Figure 1 represents a perspective view of my press.

Figure 2, a front elevation; and

Figure 3, a central longitudinal section.

The same letters occurring on the several figures indicate corresponding parts.

The nature of my invention consists in so constructing the cam-lever as to provide for elevating as well as depressing the platen, by a single device, and in so connecting the cam with the platen and bridge as to dispense with all the usual guides, whereby the press is reduced to the utmost degree of simplicity, consisting of only three castings and a small roller, which are put together by drilling but two holes for the insertion of steel wire pins, which completes the construction of the press.

To enable others skilled in manufacture to make and use my invention, I will proceed to describe its construction and operation by referring to the drawings, in which—

A represents the bed-plate, which is cast with an upright, B, at each end, of suitable height, and from the upper end of each is an arch or bridge, C, connecting the two; this much is all cast in one piece. The bridge C has a slot, D, vertically through it, extending nearly from end to end, which is formed by a core in the casting. Within this slot, near the centre of its length, is supported the eccentric E, on a pin, F, passed laterally through it and the bridge C, and on which it vibrates. The platen G is cast with two ears H, at the centre of its upper side, of sufficient distance apart to admit the eccentric E between them, the space between them being longitudinally parallel with the slot D, in the bridge, and vertically under it. These ears H are about half the diameter of the eccentric E in length, and are consequently sufficient guide to keep the platen vertically over the bed-plate, without the necessity of end guides, as commonly constructed. The eccentric E is constructed with a semi-annular slot, I, in which is inserted a roller, a, of a diameter about equal to the width of the slot I, and yet to be capable of rolling in it. The eccentric is then connected with the platen by inserting a pin, e, transversely through the ears H and rollers a. Thus it will be seen that by turning the eccentric to the left by moving the lever K in direction of the arrow, fig. 3, the platen will be raised by the roller revolving on the low side of the slot I; and in moving it in the opposite direction, the platen will be depressed by the upper side of said slot bearing on and rotating the roller, until sufficient pressure is produced; and in order to retain the lever in any desired position I insert a set-screw, u, in one side of the bridge, to pinch the cam or eccentric, and thus prevent its motion.

What I claim as new, and desire to secure by Letters Patent, is—

The slotted eccentric E, and roller a, combined and arranged with relation to the platen, G and bridge H, all constructed and operating substantially as herein set forth.

S. G. CABELL.
